[57] CLAIM

The ornamental design for a finger ring, as shown and described.

DESCRIPTION

FIG. 1 is a perspective view of a finger ring showing my new design;

FIG. 2 is a top plan view thereof;

FIG. 3 is an end elevational view thereof;

FIG. 4 is a side elevational view thereof;

FIG. 5 is a bottom plan view thereof; and

FIG. 6 is an exploded perspective view showing the ornamental features of the component parts of my ring design.
